United States Patent

Des. 238,182
Patented Dec. 23, 1975

238,182

SPEAKER ENCLOSURE OR THE LIKE

Hisashi Kizawa, Fudomae Mansion, Suite 306, 8-11-5
chome, Nishigotanda, Shinagawa-ku, Tokyo, Japan

Filed Dec. 4, 1972, Ser. No. 311,756

Term of patent 14 years

Int. Cl. D14—01
U.S. Cl. D26—14 G

Fig. 1

Fig. 2

Fig. 3

Fig. 5

Fig. 6

Fig. 4

FIG. 1 is a perspective view of a speaker enclosure or the like showing my new design;

FIG. 2 is a front view thereof;

FIG. 3 is a right side view thereof, the left side view being identical thereto;

FIG. 4 is a top plan view thereof;

FIG. 5 is a bottom plan view thereof; and

FIG. 6 is a back view thereof.

I claim:

The ornamental design for a speaker enclosure or the like, as shown.
